COMBINED DOOR HANDLE AND ESCUTCHEON

Endre Toth, St. Paul, Minn.

Application May 15, 1958, Serial No. 50,919

Term of patent 14 years

(Cl. D10—8)

Fig. 1 is a front elevational view of a combined door handle and escutcheon, showing my new design.

I claim:

The ornamental design for a combined door handle and escutcheon, substantially as shown.
